CONTAINER CLOSURE

Jay Bernard Eisen, Yonkers, N. Y., assignor to
 Ferdinand Gutmann & Co., Brooklyn, N. Y., a
 corporation of New York

Application April 17, 1935, Serial No. 16,789

7 Claims. (Cl. 215—43)

The invention relates to container closures, and more particularly to a closure for use in preserving or canning food-stuffs by a process or procedure in which vapors arising from the heated 5 contents of a container are utilized to expel atmospheric air from the container and form an hermetic joint between the closure and the mouth of the container, so that with the subsequent condensation of vapors, sub-atmospheric pressure is 10 developed within the container.

Prior to my present invention, in the production of a vacuum pack of the character above described, I used a disc of metal foil, but experimentation determined that such material alone 15 could not be used with sufficiently reliable results. This was due in part to the fact that during the preserving or canning operation there was a tendency, if a screw cap were used, to twist and wrinkle the metal foil with a resultant formation of chan- 20 nels or voids across the neck of the container through which air might gradually seep. I also have discovered that metal foil, in many instances, has small openings or weak spots therein, so that when the inner seal disc is subjected to atmos- 25 pheric pressure, air either escapes through existing openings in the foil into the container, or such openings are formed by the breaking down of the metal foil at weakened spots therein.

Another further difficulty with the use of the 30 metal foil was that the high flexibility of such thin material would, by the cupping of the disc, tend to break the bond between the disc and the mouth of the container, due to the physical movement of the disc, particularly if there were a sufficiently 35 rapid condensation of the vapors within the container as to not allow a sufficient time interval for the setting of the adhesive used.

With the above conditions in mind, I have after 40 long experimentation, provided a container closure for use in preserving or canning foodstuffs, the construction of which is such as to not only pre- 45 clude the presence of minute openings through the sealing disc, but to prevent the formation of such openings from differential pressures upon op- 50 posite sides of this disc, with the preponderating pressure exteriorly of the container and the disc. The construction of the sealing disc and of the main closure carrying same, is such as to avoid turning of the disc when applying the closure to the container or when finally affixing the main closure to the container, even though a screw threaded closure cap be used.

With the container closure embodying the in- 55 vention, there is always the possibility if a screw threaded re-seal cap be employed, that with a

premature final application of the outer closure, there may be a slight turning movement of the sealing disc notwithstanding that the purpose of the structure is to avoid such movement. This disc itself is therefore so constructed that even 5 though there be such turning movement, there can be no deformation of the disc, as by wrinkling or creasing, about the portion of the edge thereof in contact with the neck of the container. The same structure which is relied upon to prevent distortion of the disc as a result of turning movement thereof, is relied upon to impart sufficient rigidity to the disc to prevent distortion thereof, inwardly of the mouth of the container, to an extent to develop any material drag of the edge portion of 10 the disc across the edge of the mouth of the container before the adhesive has become permanently set. Such distortion can occur only from the action of ordinary atmospheric pressure upon the top of the disc, and this may occur notwithstanding the use of an outer metallic shell having a flexible liner for the purpose of supplementing the action of the disc in securing a desired permanency in the air tight joint formed between the disc and the neck of the bottle. 15

While a closure embodying the invention is suitable for use by canneries in the packaging of foodstuffs in glass jars, it is particularly adapted for use by the housewife in home preserving or canning since it may be effectively used without 20 the said of special vacuum apparatus.

In the use of a closure embodying the invention, the inner seal obviates the necessity for the formation of an airtight closure by the compression of a rubber gasket, such as is characteristic 35 of the well known Mason jar, and variations thereof, in use for more than half a century, and eliminates all possibility of failure to secure an air-tight joint because of defective gaskets and the development of inadequate compressive stresses 40 thereon.

With a closure of the invention, the difficulties of removing the closure from a container, characteristic of Mason jars, are absent, since the application of the outer cap is not relied upon to 45 form a seal but merely as a protection against the accidental breaking of the closure effected by the inner disc seal.

The invention consists primarily in a container closure embodying therein an outer closure member having a skirt adapted to co-operate with the neck of a container for retaining said member thereon, and a closure disc within, but separable from said member, consisting of a facing disc of 50 normally highly flexible, non-absorbent mate- 55

rial, a backing disc of relatively thicker compressible material having a low degree of flexibility, and having such rigidity as to prevent sufficient displacement of the facing disc from pressures resulting from sub-atmospheric pressure within a container to break the bond between the facing disc and the neck of the container, a stratum of adhesive bonding said facing disc to said backing disc, whereby relative movement of said discs is prevented and any openings through said facing disc are sealed, said facing disc and said backing disc being of substantially the same diameter and having their edges closely adjacent the skirt of said metal shell, whereby when applying the closure to a container, said facing disc will be engaged with the top of the mouth of the container, and a heat fusible dry adhesive upon the exposed surface of said facing disc adjacent the edge thereof, whereby the bond between the container and said closure member is between said facing disc and the container; and in such other novel features of construction as are hereinafter set forth and described, and more particularly pointed out in the claims hereto appended.

25 Referring to the drawing.

Fig. 1 is a view partly in elevation and partly in section of the upper portion of a container showing a closure embodying the invention applied thereto;

30 Fig. 2 is a sectional view of the top of the neck of a container with the inner sealing disc of the closure applied thereto and the outer closure member removed from the container;

35 Fig. 3 is a bottom view of the inner closure disc broken upon parallel planes to disclose the structure thereof; and

Fig. 4 is a fragmentary portion of a modified form of closure in which the outer closure member is frictionally held upon the container.

40 Like numerals refer to like parts throughout the several views.

In the embodiment of the invention shown in the drawing, an ordinary glass container, which may take any desired form, is shown at 10. As 45 illustrated in Fig. 1, the neck 11 of the container is provided with exterior screw threads 12, and the top of the neck is provided with a flat surface indicated at 13 to afford sufficient area to permit a firm bonding of an inner sealing disc thereto. As shown in Fig. 4 of the drawing, the neck of the container is so formed as to co-operate with a well known form of friction cap, the container conforming in other respects with the showing of Fig. 1.

55 The closure proper comprises an outer closure member or cap 14 which may have an imperforate top 15 and a skirt 16 provided with screw threads 17 adapted to co-operate with the screw threads 12.

60 Within said closure member is a liner 18 which may be of pulp board or any other compressible material so as to permit the use of the outer closure member for closing the container after a 65 part of the contents has been removed therefrom. The liner 18 is that commonly used in re-seal caps.

The member 14 is preferably drawn up from tin plate which may be suitably decorated, if desired, and adjacent the top 15, the skirt 16 is of greater diameter, as indicated at 19, than the portion of the skirt more remote from the top. Materials other than tin plate may be used in forming the shell of the cap 14.

75 Within, but separable from, the member 14 is

an inner closure or sealing disc consisting of a facing disc 20 ordinarily of tin foil, although the material of this disc is not essential since it may be varied in adapting a closure for use in the canning or preserving of different foodstuffs. I 5 have found, however, that it is desirable that this disc be made of thin, highly flexible, non-absorbent material in order to get practical, satisfactory results.

Said closure or inner seal disc also includes 10 therein a backing disc 21 of pulp board or other compressible material having a low degree of flexibility so as to impart a measurable degree of rigidity to the facing disc 20 and the closure disc as a whole.

15 The facing disc 20 and the backing disc 21 are firmly bonded together by means of a stratum 22 of an adhesive so as to prevent relative movement of these discs, which relative movement might result in the formation of wrinkles or creases about the edge of the facing disc, particularly if a cap 14 having a screw threaded skirt is used.

20 Applied to the exposed side of the facing disc 20 is a coating of a heat fusible dry adhesive 23. While this adhesive may be applied only adjacent the edge of the disc 20 in a band or stripe of sufficient width to engage the full area of the top surface 13 of the neck of a container, I preferably coat the entire surface of the disc therewith, since the use of a proper adhesive upon the exposed surface of the disc 20 protects the material of this disc from the contents of a container to an extent to increase the range of materials 30 which may be used in said disc.

25 I have secured excellent results in forming a bond between the disc 20 and the neck of a bottle by employing a well known form of cellulose derivative cement obtainable upon the open market, although other thermo-plastic cements, 40 having a relatively high fusing point compared with waxes, may be employed if desired. The cellulose derivative cements, however, have the advantage that they soften readily at temperatures approaching the boiling point of water 45 and are not affected by normal kitchen temperatures. Furthermore, such adhesives do not deteriorate over long time intervals and are more or less free flowing when once softened, so as to readily adapt themselves to small irregularities in the surfaces of the two articles to be bonded together. They are not deleteriously affected by contact with the contents of the container, do not have any characteristic flavor to impart to such contents, and are highly liquid 50 repellent.

55 The laminated, or composite, inner closure or sealing disc is of a diameter relatively less than the top of the outer closure, but of slightly larger diameter than the lower portion of the skirt thereof. With this arrangement, said disc 20-23 has a free floating relation to the outer closure, so that there is little or no likelihood of the turning of said disc with said outer closure when applying the closure to a container, or if the outer closure be tightened before the cement or adhesive forming the bond between the inner closure or sealing disc and the neck of the container has fully set.

60 The embodiment of the invention shown in Fig. 4 differs from that shown in Figs. 1 and 2 merely in the form of the shell of the outer closure. This shell, 14a, has an imperforate top 15a and a skirt 16a so formed as to frictionally engage the neck 11a of a container 10a. 65

The inner closure or seal used is the same as that heretofore described, so that the same reference letters are applied to the different laminae thereof.

5 In the use of a cap embodying the invention, the jars 10 are filled with foodstuffs, which are either at a temperature approximating 212° F. or are brought to this temperature, and a closure embodying the invention is applied to the 10 container. The inner seal or closure disc is then brought into contact with the surface 13 of the container, by movement of the outer closure member 14 or 14a, either by a turning action 15 of the closure, or by a direct movement thereof toward the neck of the bottle when a friction cover is used as illustrated in Fig. 4. It is merely required that the coating 23 of adhesive be brought into contact with the surface 13, it being undesirable to develop any material pressure 20 between the inner closure disc and the neck of the container, since it is required that the conditions be such as to permit the venting of air and vapor from the container between the surface 13 and the adhesive coating 23 until the 25 pressure of said vapors within the container equals atmospheric pressure. The time required to bring about this equilibrium of pressure is adequate to soften or fuse the cement of the coating 23, and when this occurs an airtight seal 30 is formed about the mouth of the container, so that with the subsequent cooling of the container and its contents, a vacuum, or sub-atmospheric pressure, will be developed as a result of the condensation of the vapors within the 35 container. Since the adhesive sets in the course of a very few seconds, the effectiveness of the bond increases as the container and its contents cool. This is because of the preponderating pressure upon the top of the inner closure disc.

40 Looseness of the outer closure 15 is desirable since it not only permits the escape of air and vapor until the bond has been made, but also admits air at normal pressures upon the top of the inner closure disc so as to utilize such pressure in forming the bond.

I have found that in wide mouthed jars if metal foil be used for the disc 20, the aggregate pressure upon the top of the disc, and the relatively low pressure within the container, below 50 the disc, will tend to draw the disc within the container, or cup it inwardly to an extent to cause it, adjacent its edge, to drag across the surface 13 to an extent to break the vacuum or sub-atmospheric pressure within the jar and 55 destroy the effectiveness of the seal. This can occur only before the adhesive coating 23 has set sufficiently to ensure a permanent bond between the disc 20 and the container.

While the adhesive 23 is capable of setting 60 rapidly as heretofore stated, slow cooling of the container and its contents may delay the setting of the adhesive, although an hermetic joint will be formed before the adhesive has finally set. Such slippage of the disc 20, if used alone, 65 may not occur frequently, nevertheless there is always a possibility of the spoilage of the foodstuffs because of such slippage, and since the use of the semi-rigid backing disc 21 will resist deformation of the disc from exterior pressure 70 to an extent to positively prevent such movement of the disc 20, the practicability of the closure is secured solely by means of this disc 21. Deformation or inward cupping of the disc 20, if used alone, may result in the formation of 75 channels between the disc and the neck of the

bottle, due to reduction in the diameter of the disc by such cupping. The disc 21, firmly bonded to said disc 20, in resisting such deformation or cupping of the latter, prevents this action.

The stratum 22 of adhesive is used mainly 5 for the purpose of preventing relative movement of the discs 20 and 21, to prevent wrinkling or creating of the thin material of the disc, and close any minute openings in the material of the disc 20. This adhesive stratum, however, 10 also prevents any possible seepage of air between the two discs. This last feature is highly desirable in a closure structure, the use of which 15 contemplates the presence of air passages about the neck of the container in the manner above referred to, in securing the formation of an airtight or hermetic joint independently of the main outer closure. The outer closure 14 is used to prevent displacement of the inner closure or sealing disc while forming the airtight 20 joint, to protect said disc from possible rupture while the container is in storage and to permit re-sealing of the container after a portion of the 25 contents thereof has been removed.

When it is desired to remove the contents of 25 the container, the outer closure or cap 14 is removed by hand, no tools of any kind being required, and there being little resistance to the removal thereof since an airtight joint is secured without the aid of this closure. After said 30 closure 14 is removed, the inner closure is removed by hand, or if desired, the closure may be so heated as to soften the adhesive 23 so that 35 the inner closure or sealing disc may be freely lifted from the container.

From the foregoing it is obvious that in preserving or canning foodstuffs, it is merely necessary to apply the closure of the invention to the container without attempting to tighten same 40 thereon, and that the heat incidental to the preserving or canning operation will result in the formation of an effective airtight joint, so that the subsequent cooling of the contents of the container and the resulting condensation of the 45 vapors at the top thereof will develop the desired vacuum or sub-atmospheric pressure to complete the formation of the seal and establish and maintain conditions in the container which will prevent bacteriological action within the container.

It is not my intention to limit the invention to 50 the particular materials of which the discs 20 and 21 are formed, the particular adhesive used in the coatings 22 and 23, or the particular thickness of the discs 20 and 21. Ordinarily, the material of the disc 20 will be about .003 of an inch or less, while that of the disc 21 is .02 of an inch. The adhesives used and the materials in, and thickness of, the discs 20 and 21, are subject to 55 considerable variation. A thicker disc 21 is required for use with wide mouthed jars than with smaller mouthed containers.

In other words, the degree of rigidity of this disc 21 must be proportionate to the aggregate pressure to which it may be subjected. While 60 the pressure per square inch will be substantially constant, the aggregate pressure resulting in deformation of the inner closure or sealing disc is determined by the diameter of this disc.

Having described the invention, what I claim as 65 new and desire to have protected by Letters Patent, is:—

1. A container closure embodying therein an outer closure member having a skirt adapted to co-operate with the neck of a container for re- 70

taining said member thereon, and a closure disc within, but separable from said member, consisting of a facing disc of normally highly flexible, non-absorbent material, a backing disc of relatively thicker compressible material having a low degree of flexibility, and having such rigidity as to prevent sufficient displacement of the facing disc from pressures resulting from sub-atmospheric pressure within a container to break the bond between the facing disc and the neck of the container, a stratum of adhesive bonding said facing disc to said backing disc, whereby relative movement of said discs is prevented and any openings through said facing disc are sealed, 5 said facing disc and said backing disc being of substantially the same diameter and having their edges closely adjacent the skirt of said metal shell, whereby when applying the closure to a container, said facing disc will be engaged with the top of the mouth of the container, and a coating of dry, heat fusible adhesive throughout the exposed surface of said facing disc, whereby the bond between the container and said closure member is between said facing disc and the container. 10

15 2. A container closure embodying therein an outer closure member having a skirt provided with a portion, adjacent the top thereof, of greater diameter than toward the bottom, said skirt being adapted to co-operate with the neck of a container for retaining said member thereon, and a closure disc within said member of smaller diameter than the portion of the skirt toward the top thereof, whereby said disc has a full floating 20 relation to said outer closure and is separable therefrom, said disc consisting of a facing disc of normally highly flexible, non-absorbent material, a backing disc of relatively thicker compressible material having a low degree of flexibility 25 and having such rigidity as to prevent sufficient displacement of the facing disc from pressures resulting from sub-atmospheric pressure within a container to break the bond between the facing disc and the neck of the container, a stratum of adhesive bonding said facing disc to said backing disc, whereby relative movement of said discs is prevented and any openings through said facing disc are sealed, said facing disc and said backing disc being of substantially the same diameter and 30 having their edges closely adjacent the skirt of said metal shell, whereby when applying the closure to a container, said facing disc will be engaged with the top of the mouth of the container, and a coating of dry, heat fusible adhesive 35 throughout the exposed surface of said facing disc, whereby the bond between the container and said closure member is between said facing disc and the container.

40 3. A container closure embodying therein an outer closure member having a skirt adapted to co-operate with the neck of a container for retaining said member thereon, and a closure disc within, but separable from said member, consisting of a facing disc of normally highly flexible, 45 non-absorbent material, a backing disc of relatively thicker compressible material having a low degree of flexibility, and having such rigidity as to prevent sufficient displacement of the facing disc from pressures resulting from sub-atmospheric pressure within a container to break the bond between the facing disc and the neck of the container, a stratum of adhesive bonding said facing disc to said backing disc, whereby relative movement of said discs is prevented and any openings through said facing disc are sealed, said 50

facing disc and said backing disc being of substantially the same diameter and having their edges closely adjacent the skirt of said metal shell, whereby when applying the closure to a container, said facing disc will be engaged with the top of the mouth of the container, and a coating of dry, heat fusible adhesive throughout the exposed surface of said facing disc, whereby the bond between the container and said closure member is between said facing disc and the container. 5

55 4. A container closure embodying therein an outer closure member having a skirt provided with a portion, adjacent the top thereof, of greater diameter than toward the bottom, said skirt being adapted to co-operate with the neck of a container for retaining said member thereon, and a closure disc within said member of smaller diameter than the portion of the skirt toward the top thereof, whereby said disc has a full floating 60 relation to said outer closure and is separable therefrom, said disc consisting of a facing disc of normally highly flexible, non-absorbent material, a backing disc of relatively thicker compressible material having a low degree of flexibility 65 and having such rigidity as to prevent sufficient displacement of the facing disc from pressures resulting from sub-atmospheric pressure within a container to break the bond between the facing disc and the neck of the container, a stratum of adhesive bonding said facing disc to said backing disc, whereby relative movement of said discs is prevented and any openings through said facing disc are sealed, said facing disc and said backing disc being of substantially the same diameter and 70 having their edges closely adjacent the skirt of said metal shell, whereby when applying the closure to a container, said facing disc will be engaged with the top of the mouth of the container, and a coating of dry, heat fusible adhesive 75 throughout the exposed surface of said facing disc, whereby the bond between the container and said closure member is between said facing disc and the container.

75 5. A container closure embodying therein an outer closure member having a skirt adapted to co-operate with the neck of a container for retaining said member thereon, and a closure disc within, but separable from said member, consisting of a facing disc of metal foil, a backing disc of relatively thicker compressible material having a low degree of flexibility, and having such rigidity as to prevent sufficient displacement of the facing disc from pressures resulting from sub-atmospheric pressure within a container to break the bond between the facing disc and the neck of the container, a stratum of adhesive bonding said facing disc to said backing disc, whereby relative movement of said discs is prevented and any openings through said facing disc are sealed, 80 said facing disc and said backing disc being of substantially the same diameter and having their edges closely adjacent the skirt of said metal shell, whereby when applying the closure to a container, said facing disc will be engaged with the top of the mouth of the container, and a heat fusible dry adhesive upon the exposed surface of said facing disc adjacent the edge thereof, whereby the bond between the container and said closure member is between said facing disc and the container.

85 6. A container closure embodying therein an outer closure member having a skirt adapted to co-operate with the neck of a container for retaining said member thereon, and a closure disc 90

5

10

15

20

25

within, but separable from said member, consisting of a facing disc of metal foil, a backing disc of pulp board of a thickness to possess a lower degree of flexibility, and having such rigidity as to prevent sufficient displacement of the facing disc from pressures resulting from sub-atmospheric pressure within a container to break the bond between the facing disc and the neck of the container, a stratum of adhesive bonding said facing disc to said backing disc, whereby relative movement of said discs is prevented and any openings through said facing disc are sealed, said facing disc and said backing disc being of substantially the same diameter and having their edges closely adjacent the skirt of said metal shell, whereby when applying the closure to a container, said facing disc will be engaged with the top of the mouth of the container, and a heat fusible dry adhesive upon the exposed surface of said facing disc adjacent the edge thereof, whereby the bond between the container and said closure member is between said facing disc and the container.

7. A container closure embodying therein an outer closure member having a skirt provided with a portion, adjacent the top thereof, of greater diameter than toward the bottom, said skirt being adapted to co-operate with the neck of a con-

tainer for retaining said member thereon, and a closure disc within said member of smaller diameter than the portion of the skirt toward the top thereof, whereby said disc has a full floating relation to said outer closure and is separable therefrom, said disc consisting of a facing disc of metal foil, a backing disc of pulp board of a thickness to possess a lower degree of flexibility and having such rigidity as to prevent sufficient displacement of the facing disc from pressures resulting from sub-atmospheric pressure within a container to break the bond between the facing disc and the neck of the container, a stratum of adhesive bonding said facing disc to said backing disc, whereby relative movement of said discs is prevented and any openings through said facing disc are sealed, said facing disc and said backing disc being of substantially the same diameter and having their edges closely adjacent the skirt of said metal shell, whereby when applying the closure to a container, said facing disc will be engaged with the top of the mouth of the container, and a coating of dry, heat fusible adhesive throughout the exposed surface of said facing disc, whereby the bond between the container and said closure member is between said facing disc and the container.

JAY BERNARD EISEN.
